CLAIM

We claim the ornamental design for the adjustable hitch for towing, as shown and described.

DESCRIPTION

FIG. 1 is a front and side perspective view of the adjustable hitch for towing showing our new design;

FIG. 2 is a top view of the hitch shown in FIG. 1;

FIG. 3 is a front view of the hitch shown in FIG. 1;

FIG. 4 is a left-side view of the hitch shown in FIG. 1;

FIG. 5 is a right-side view of the hitch shown in FIG. 1;

FIG. 6 is a reverse top view of the hitch shown in FIG. 2; and,

FIG. 7 is a rear view of the hitch shown in FIG. 1.

The ornamental design for a hitch for use in coupling to a vehicle, boat or other items.
